UNITED STATES PATENT OFFICE

RAYMOND H. MOORE, OF HARVEY, ILLINOIS, ASSIGNOR TO WHITING CORPORATION,
OF HARVEY, ILLINOIS, A CORPORATION OF ILLINOIS

DUST ARRESTER

Application filed February 26, 1927. Serial No. 171,127.

The present invention relates to dust arresters.

One object of the invention is to provide an arrester, which is composed of assembled individual units with frames and fabric in which the margins of the fabric are padded to reduce the wear thereon; which is composed of individually-supported framed screening units; in which such units are individually removable and replaceable and of improved sectional construction; which is composed of like screening units which provide for a substantially full discharge area from the screen; and in which the screening units are vibrated by pulsations, as distinguished from violent shocks to avoid wear of the fabric in the units.

Another object of the invention is to provide a dust arrester which is generally of new and improved construction, may be manufactured at a low cost and is exceedingly efficient in operation.

Other objects of the invention and the various advantages and characteristics of the present dust arrester construction will be apparent from a consideration of the detailed description.

The invention consists in the several novel features hereinafter set forth and more particularly defined by claims at the conclusion hereof.

In the drawings which accompany and form a part of this specification or disclosure and in which like numerals and characters of reference denote corresponding parts throughout the several views; Fig. 1 is a transverse section of an arrester embodying the invention. Fig. 2 is a horizontal section. Fig. 3 is a section taken on the line 3-3 of Fig. 2. Fig. 4 is a horizontal section through several of the screening units and one of the side walls. Fig. 5 is a sectional perspective illustrating the construction of the screening units. Fig. 6 is a perspective of one of the screening units. Figs. 7, 7^a, 8 and 8^a are perspectives, illustrating details of a screen frame. Fig. 9 is a vertical section through the vibrating device. Fig. 10 is a section on the line 10-10 of Fig. 9.

Fig. 11 is a detail of the outlet valve for the accumulated dust.

The dust arrester which forms the subject matter of this invention comprises, a casing A which is preferably of metal plate construction and is mounted upon a supporting frame B of any desired construction. The casing comprises a back wall a¹ to which is connected an air intake a²; a bottom comprising discharge hoppers a⁴ and a⁵ and a floor section a³ in front of the hoppers and secured on channel-beams a³⁰; a front wall a⁶ to which is connected an air discharge pipe a⁷ for conducting the purified air from a transverse chamber a²⁰ at the front of the casing; a top wall a⁸, and side walls a⁹ and a¹⁰. The casing is built up mainly of metal plates which have their contiguous margins provided with right angled flanges a¹¹ and a¹² to form a lapped seam between which suitable packing, such as tar paper, is interposed, the flanges being bolted together. One of the contiguous flanges is preferably reverted, as at a¹³, to close the edge of the seam. A baffle a¹⁴ which is spaced by brackets 10 from the intake a², is provided to deflect the air laterally and cause it to be distributed transversely of the receiving chamber a²⁰ at the back of the casing. Suitable means, such as an exhaust fan or blower 80 will be used to force the dust laden air through the casing. The casing contains a series of screening units which are alike in construction, so that the capacity of the arrester may be varied by varying the number of the screening units. The sectional plate construction hereinbefore described permits of the expansion of the casing for this purpose. To the top a⁸ of the casing is secured a channel bar 15, to which the upper ends of the screening units are secured, as hereinafter set forth. A channel 16 extends transversely across the frame adjacent the bottom thereof to support and retain the lower front ends of the screen units. This channel is formed of a metal bar comprising a web 17 (Fig. 5) with an upwardly extending flange 18 and a downwardly extending front flange 19 and a removable strip 20 which permits the screen 190

units to be placed in and removed from channel 16 upon removal of the bolts 21 which secure the strip against flange 19. The plates, forming the top and bottom and the front and back of the casing, overlap one another, and strips of tar paper 22 are placed between the laps to seal the joints against leakage of air. Similar strips 22^a are also placed in the top seams between the 10 rims of hoppers a^4 and a^5 and the side walls and flange 19, and between the top of channel 15 and top a^8 , to prevent air from passing into chamber a^{60} without passing through the screens. A door 23 is usually 15 provided in the front wall a^6 to provide access to the front ends of the screening units and to chamber a^{60} in the casing.

The screening units, generally designated "C", are adapted to fit together side-by-side, 20 and are alike in construction, so that arresters of different sizes and capacities may be built up by varying the number of units and the width of the casing. Each unit C comprises a frame and suitable fabric D, such 25 as cloth. The fabric is applied so as to form rectangular side pieces which extend over the sides of the frame and through which air must pass in transit from the inlet chamber a^{20} to the exhaust chamber a^{60} . This 30 fabric is adapted to arrest the dust so it will fall into, hoppers a^4 and a^5 in which it will accumulate. Each screen-frame comprises a bottom rail c^1 , a back rail c^2 , a top-rail c^3 , a pair of front corner bars c^4 and c^5 which 35 are spaced apart by the top and bottom rails, and a series of intermediate horizontal rails c^6 which have their rear ends secured to the back rail and their front ends terminating between, and flush with, the 40 front corner rails. Diagonal stay-wires c^7 are stretched across and secured to the sides of the frame to hold the fabric D at the frame-sides. These wires are secured to the bars c^6 by staples c^8 and are lapped around 45 nails c^9 on the top and bottom rails of the frame. In practice, it has been found that when the cloth used in these screening units is directly secured to the frame, it soon becomes worn as the result of the vibration to 50 which the frames are subjected to cause the fabric to release the dust. To overcome this disadvantage, the cloth D is spaced from the side faces of the frame-members by padding. The latter is in the nature of strips 55 of cord d which are secured to the frame by nails d^2 before the cloth is secured in place. These cords d extend lengthwise of the top and bottom rails c^1 and c^3 of the frame and upwardly at the rear corners of the rear 60 upright c^2 of the frame, so that the cloth will be correspondingly spaced from the frame-sides, and the cord will form a padding or cushion between the frame and the cloth. Preferably, the cloth extends continuously across the back of the rear rail c^2 , as

at d^3 , (Fig. 5). The cord d also spaces the fabric from the heads of the nails c^9 used for securing the stay wires c^7 to the top and bottom rails of the frame.

To secure the top and bottom margins of the cloth of the rails c^1 and c^3 respectively, grooves c^{10} are formed in the side faces of said rails immediately below the cord d on the bottom rail c^1 and above the cord d on the top rail c^3 and around the back of said rails, and bottom margins of the cloth D are folded into said grooves and secured therein by a cord d^4 which fits snugly in the groove and is secured therein by nails d^5 , so that these margins of the cloth will be securely connected to the frame and so that when it is desired to replace the cloth, it may be readily removed upon removal of the cords d^4 . When secured in the grooves, these cords serve as a marginal reinforcement at the points where the cloth is secured to the frame. The front margins of the cloth D are secured against the back faces of the front bars c^4 and c^5 by vertical strips d^6 which are conterminous with the upper and lower ends of said bars. The front margins of the cloth are extended to lap portions of the side faces of the bars c^4 and c^5 and are there secured by nails d^7 to said bars.

The upper ends of the bars c^4 , c^5 and strips d^6 are extended a short distance above the top rail c^3 . The space between the projecting portions of the bars and strips are filled by a block c^{11} . A bolt c^{12} (Fig. 6) extends vertically through top rail c^3 , block c^{11} and through the lower flange of the channelled beam 15 of the casing to independently support the upper portion of each screen frame in place. The lower ends of the bars c^4 and c^5 and strips d^6 of each screen frame are also extended to project below the lower rails c^1 , and blocks c^{13} are suitably secured between the projecting ends thereof. The downwardly projecting portions of these bars and strips fit into the channel 16 of the 110 casing. A strip of felt 25 extends over the top of the projecting portion at the top and front of the screen frame and across the front and back thereof, to form an air-tight joint between the frame and the channel-bar 15. 115 A strip of felt 26 extends across the lower end and front and back faces of the lower projecting portion of each frame, to seal the joint between the frame and the channel 16, in which it is seated. The outer side face of each bar c^5 of one screen frame is adapted to abut against the outer face of a bar c^4 of a contiguous frame, so that when fitted together they will form a front closure for the 120 spaces between the screen cloths of contiguous frames. To additionally prevent dust from passing between the frames, the bars c^4 and c^5 are each formed with a vertical groove c^{14} and strips of cloth d^8 are stretched across the joint between the front bars of 125

the frames with their margins folded into the grooves of contiguous front bars of the screen frames and are secured therein by strips of cord d^9 which are pressed into the 5 grooves over the cloth and secured therein by nails d^{10} . Spacing blocks c^{15} (Fig. 2) are secured to the back rails c^2 on the outside of the cloth to keep the rear portions of the frames properly spaced and so the parallelism of the frames will be maintained.

10 The air is forced from the inlet chamber a^{20} at the back of the casing into the spaces between the screen frames and thence through the screen cloths and into the frames, 15 and thence forwardly through the spaces between the front bars of the frame, the dust in the air being arrested by the cloth.

15 The screen unit thus described exemplifies one which constitutes a complete unit which 20 may be individually supported and removed; in which the fabric is padded or cushioned and held in spaced relation from the frame to reduce the wear on the fabric; in which the margins of the cloth are extended into 25 grooves held therein by cords, so that when the cloth becomes worn, it may be readily removed and replaced; in which there is practically a full area of inlet and discharge in each unit; and in which the front frame 30 bars project above and below for convenient attachment to bars in the casing.

35 In dust arresters of this type, it has been the usual practice to provide mechanism for tapping the structure to subject the cloth to vibration which will cause it to release the dust so it will be deposited in the discharge hoppers. In practice, it has been found that mechanism which imparts a succession of sharp shocks to the frame results in causing 40 rapid wearing out of the cloth. To overcome this objection, the present invention provides a mechanism for producing rapid pulsations of the screening units, as contradistinguished from sharp vibrations, or shocks. This 45 mechanism comprises an electric motor E , which is suspended from a board secured to brackets e^1 which are secured to the front a^6 of the casing. A metal channel bar e^2 extends across the front of all or a series of 50 screen units and is secured to each by a pair of bolts e^3 which are fixed in blocks e^4 which are secured to the frame between the front bars thereof, so that the bar e^2 will be rigidly secured to the entire series of screen frames. 55 A vertically extending bracket or base e^5 is secured to the longitudinal center of the bar e^2 and is provided with a forwardly projecting stud e^6 on which is held an inner race e^7 for a series of anti-friction balls e^8 . An eccentric or unbalanced weight or member e^9 extends around stud e^6 and carries the outer race e^{10} for said balls which form an anti-friction bearing between the unbalanced member and the bracket. A hollow coupling 60 member e^{11} is screw-threaded into the front

face of the pulsating member e^9 and secured to the rear end of a shaft e^{12} . Said shaft is driven from the shaft e^{13} of the motor E by a flexible coupling comprising a member e^{14} secured to shaft e^{13} , a member e^{15} secured to the front end of shaft e^{12} and an elastic driving sleeve e^{16} which is secured to reduced portions of the members respectively so as to constitute a flexible driving connection for the pulsating device which will not transmit the pulsations of the electric motor. The rapid rotation of the member e^9 , which will impart vibrations or pulsations which will be transmitted through bracket e^5 to the pulsating bar e^2 . The ball-bearing for the pulsating member is disposed inside thereof, so that all the load will be carried by the bracket e^5 without transmitting the pulsations to the motor. The member e^{11} is provided with a chamber e^{17} which is adapted to contain lubricant for the ball-bearing. A packing ring e^{18} is held in the inner end of the member e^9 to prevent the lubricant from escaping. The ball race e^7 is secured on stud e^6 by a bolt e^{19} provided at its inner end with a nut and washer for clamping the race on the stud. Coupling member e^{14} may be unscrewed from the pulsating member e^9 and has a plug e^{20} so the chamber e^{17} may be refilled when desired.

95 The invention thus exemplifies a device which is adapted to impart pulsations to the screen units to cause them to deposit the dust collected by the cloths without subjecting them to sharp shocks or vibrations, and this has been found to prevent the loosening of the fastenings of the fabric and the resultant wear of the fabrication; also a construction in which the pulsating device operates without imparting vibrations to the electric motor which drives it.

100 In the operation of dust arresters of this type, it is desirable to provide means for effectively and positively closing a valve for discharging dust. For this purpose, a valve casing F is secured to the apex of each of the discharge hoppers a^4 and a^5 which is provided with a guide f^1 , in which a stem f^2 is free to slide vertically. A manually operable lever f^3 , pivoted to the casing, as at f^4 , is adapted to engage the lower end of the stem f^2 , to lift it, together with a valve f^5 , which is secured to the upper end of the stem. The casing is provided with an annular flange f^6 which extends upwardly into the hopper and a valve seat consisting of a cylindrical elastic ring f^7 fitted around said flange and extending upwardly therefrom. Valve f^5 is conoidal, and its rim is flared outwardly and downwardly to engage the upper edge of the elastic seat ring f^7 . When the valve is closed, it will be seated on the elastic ring and will form an efficient closure to prevent air or dust from escaping through the valve. The casing F is provided with an outlet spout f^8 which leads downwardly from the flange f^6 .

This construction exemplifies a valve for controlling the discharge of dust from the dust arrester which forms an efficient closure. The conoidal valve, seating on the edge of the cylindrical ring, will not result in any leakage when there is collection of dust on said ring.

The invention is not to be understood as restricted to the details set forth, since these 10 may be modified within the scope of the appended claims, without departing from the spirit and scope of the invention.

Having thus described the invention, what I claim as new and desire to secure by Letters 15 Patent, is:

1. In a dust arrester, the combination of a casing provided with an air-inlet and an air-outlet, a series of screen units each comprising a frame and fabric sides, a flanged 20 bar at the top of the casing, blocks fixed in the upper front corners of the frames, bolts passing through the blocks and flange to secure removably the frames to said bar, and means for removably securing the lower 25 front corners of the frame in the casing.

2. In a dust arrester, the combination of a casing provided with an air-inlet and an air-outlet, a series of screen units each comprising a frame and fabric sides, a flanged 30 bar at the top of the casing, blocks fixed in the upper front corners of the frames, bolts passing through the blocks and flange to secure removably the frames to said bar, and means forming a channel in which the lower 35 front corners are held, said means comprising a removable bar for clamping the lower front corners in the channel.

3. A filter device for a dust arrester, consisting of, a series of independently and individually formed and secured screening units 40 each comprising a frame and a screen fabric extending over the sides of the frame, the front faces of the frames being provided with grooves and sealing strips lapping the 45 joints between the frames and secured in said grooves.

4. A filter device for a dust arrester, consisting of a series of independently and individually formed screening-units each comprising a frame having spaced vertical front 50 bars, and a screen fabric extending over the sides of the frame, the front-bars being provided with vertical grooves in the front faces thereof and sealing strips lapping the joints 55 between the frames and secured in said grooves.

5. In a dust arrester, the combination of a casing provided with an air-inlet and an air-outlet, and a series of screening-units disposed in the casing said casing being built up of plates so its width may be varied, the plates having angular flanges secured together to form joints, one flange of each joint being reverted to extend around the edge of 60 the other flange.

6. A filter device for a dust arrester, consisting of a series of screening units each comprising a frame, fabric side-pieces covering the sides of the frame, and padding extending between and spacing apart the margins of the fabric side-pieces and the side faces of the frame. 70

7. A filter device for a dust arrester, consisting of a series of screen units each comprising a frame, fabric side-pieces covering the sides of the frame, and strips of cord between and spacing apart the margins of the fabric side-pieces and the side faces of the frame. 75

8. A filter device for a dust arrester, consisting of a series of screening units each comprising a frame, fabric sides, a cord between and spacing apart the margins of the fabric sides and the side faces of the frame, the frame having grooves arranged outwardly of the cord into which the edges of the fabric sides are extended, and strips secured in said grooves to secure the fabric in place. 80

9. A device for vibrating the filter frames of a dust arrester to release the dust, said device comprising an unbalanced member rotatably supported by the frames and adapted to vibrate the latter, and means for rotating said member. 90

10. A device for vibrating the filter frames of a dust arrester to release the dust, said device comprising a bar fixed to the frames and provided with a laterally extending stud, an unbalanced rotary member rotatably mounted on the stud, and means for rotating said member. 95

11. A device for vibrating the filter units of a dust arrester to release the dust, said device comprising an electric motor, a vibrating member for the units rotatably supported by the units, and a flexible driving connection for the member driven by the motor, to prevent the vibrations from being transmitted to the motor. 105

12. A device for vibrating the filter units of a dust arrester to release the dust, said device comprising an electric motor, an unbalanced vibrating member rotatably supported by the units, and a flexible driving connection for the member, driven by the motor, prevent the vibration from being transmitted to the motor. 110

13. A device for vibrating the filter units of a dust arrester to release the dust, said device comprising an electric motor, an unbalanced vibrating member rotatably supported by the units, and a flexible driving connection for the member, consisting of an elastic sleeve, driven by the motor, to prevent the vibration from being transmitted to the motor. 115

14. A device for vibrating the filter frames of a dust arrester to release the dust, said device comprising an element fixed to the frames, means for vibrating said element to 120 130

vibrate the frames comprising an unbalanced member having a portion thereof extending around said element, a ball bearing between said portion and the element, and means for rotating the member.

5 Signed at Harvey, Illinois, this 31st day of December, 1926.
